COMBUSTION CONTROL SYSTEM

Charles H. Smith, Newark, N. J., assignor to L. J. Wing Mfg. Co., New York, N. Y., a corporation of New York

Application January 5, 1940, Serial No. 312,461

11 Claims. (CL. 110—54)

The present invention relates to a system of combustion control for low pressure heating boilers using solid fuel and to the apparatus forming part of said system.

5 Perhaps the greatest inconvenience in the use of solid fuel boilers is the necessity for frequent attendance thereof. This is especially true when low pressure heating boilers are fired with the cheaper grades of coal, such as buckwheat, barley and rice. When using such grades of coal, particularly rice coal, low grade bituminous, briquettes and the like, which require forced draft blowers for their proper combustion, it is necessary to stroke the boiler frequently, sometimes as often as every one half hour or less.

10 The heating industry has, therefore, been seeking some method of operating boilers which would require less labor and attention and still permit the use of these cheaper grades of coal.

15 The present invention contemplates the provision of a system which is designed to utilize the cheaper as well as the better grades of coal, and yet which requires comparatively little attention. In ordinary commercial installation, such as those furnishing heating service to apartment houses, offices, schools, hospitals, institutions and industrial structures, the present system has been found to be capable of completely 20 automatic operation for periods of twenty-four and even forty-eight hours in extreme weather with heavy loads. Under light loads, such as the supplying of summer hot water, one firing per week has been found adequate. The value of the present system can be appreciated when comparison of the above figures is made with the requirements of the ordinary commercial installation which requires stoking several times daily and oftentimes one half hourly.

25 Furthermore, since my system does not require the use of high grade coal, although it is capable of utilizing the same with attendant advantages, a considerable economy in heating costs results from its use.

30 In most commercial buildings, heat is turned off during the night and the fire in the boiler is banked. Therefore, with the conventional systems now employed, in changing from nighttime to daytime heating, a heavy load is put on the heating system to reheat the furnace, the water in the boiler, the risers, and the pipes which have become cold during the night.

35 With the system of the present invention, the fire is not banked in the boiler but is operated to maintain a water temperature in the boiler just below the boiling point. Thus, during the night,

the furnace is maintained at a minimum temperature which assures the water return, the steam pipes, and the heating system in general being kept warm.

With the present system of control, therefore, 5 the heavy morning reheating load is eliminated.

Furthermore, water hammer which usually occurs in the morning when cold pipes are reheated is reduced or eliminated. The entire building in which the system of the present invention is installed is kept at a more steady and comfortable 10 building temperature.

It is recognized that boilers are heated by (a) conduction of the heat of the gases of combustion, and (b) radiation of heat from an intense 15 fire of the fuel bed, the latter requiring high rates of fuel combustion per unit of grate area.

In the conventional system, extremely high rates of heat transfer are required to meet the demands of the sudden and extreme changes of 20 the heating load, such as are encountered in the early morning. In such conventional systems, reliance must, therefore, be placed largely upon radiant heat requiring an extremely high rate 25 of fuel combustion attendant with high fuel bed fire intensity.

With the cheaper grades of fuel and the conventional system, a relatively thin fuel bed must be provided in order to present the radiant heat of the fire directly to the boiler heating surfaces 30 and to prevent the formation of clinker in the fuel bed.

The present system of control, on the other hand, is arranged to operate largely by conduction rather than by radiation, thereby reducing 35 the rate of fuel combustion and the number of stokings required and eliminating the formation of clinker. The efficiency of the entire system is thereby increased, reducing, in addition, fuel consumption.

40 Further and other advantages and objects of the present invention will be apparent from the following description and the drawings in connection therewith, in which

Fig. 1 is a schematic diagram of a steam boiler, 45 a control board panel, and connections between said boiler and control board panel, which embody the present invention.

Fig. 2 is a schematic diagram of the control board panel shown in Fig. 1.

50 Any standard type of steam producing boiler 40 may be utilized in the present system. While boilers of large fuel capacity are preferred, in almost all cases in actual practice the ordinary size boiler is adequate, since the boiler in the 55

conventional heating plant possesses reserve capacity in order to meet the peak heating requirements, such as when changing from night to day heating. A low pressure steam heating boiler is used in the illustration of my invention, though it will be understood that my invention may be applied to other heating boilers, such as the water or vapor type or boilers of high operating pressure.

10 Unlike the conventional systems, which require that the boiler be stoked frequently with thin layers of coal arranged on the bed, with the present system, the boiler 10 is required to be fired not more frequently than once every twenty-four hours. Instead of a thin layer of coal, however, the boiler 10 is filled to the top, the coal above the burning area being utilized as reserve fuel and automatically fed by means of gravity to the bed. I, therefore, utilize the relatively ample 15 space found above the conventional boiler. This type of stoking is not possible with systems which depend for their heating upon the radiant energy from the fire bed, but is possible with the present system which is adapted to operate upon conduction 20 of the heat by the gases generated during combustion.

After the boiler 10 has been stoked, the combustion of fuel is automatically maintained during the day to provide, within selected limits of 30 steam pressure, the quantity of steam required for the heating load. At night, it is automatically adjusted so as to produce a temperature just below the boiling point, such as between 190 to 200° Fahrenheit. Thus, the water in the boiler 35 and the pipes leading thereto are kept warm throughout the night and consequently the usual morning load required to change from night to day heating is reduced or eliminated. This results in a saving of fuel and provides a more 40 steady and comfortable building temperature. There is no abrupt drop in room temperature at night as occurs in the usual system when the fire in the boiler is damped.

With the cheaper grades of coal, the ordinary 45 draft from the chimney is not adequate to provide proper combustion. Therefore, in order to adapt the boiler 10 to use the cheaper grades of coal, I provide a forced draft blower 12 driven by an electric motor 14 or some similar means of 50 power. When the coal in the boiler 10 is to be burned rapidly, the motor 14 and the blower 12 are operated. When, however, the coal in the boiler is to be burned at a slower rate, the motor 55 is shut off and combustion is then maintained by the chimney draft.

In order that the fuel bed may have an ample supply of air, under influence of the chimney draft, when the blower is not in operation, I prefer 60 to use a propeller type of blower, the casing 13 and ashpit duct 15 of which, for practical purposes, present a substantially unimpeded passage, though it will be understood that other suitable forced draft means may be provided.

65 The present system is provided with a pressurestat which will automatically cause operation of the motor 14 and blower 12 when the pressure in the boiler falls below a preselected magnitude, thereby increasing the rate of combustion and 70 raising the boiler pressure to the selected magnitude, when operation of the blower motor is automatically stopped.

Sometimes, however, even though the blower is 75 no longer operating the chimney draft itself may be sufficient to cause the boiler pressure to fur-

ther rise. This is customarily known as "creeping." To prevent creeping, I provide a check draft 16 in the breeching 18 leading from the boiler to the chimney. This check damper is arranged to be automatically opened when the motor 14 is shut off and "creeping" occurs, to thereby check the ashpit draft and prevent the pressure in the boiler rising beyond the selected magnitude.

The check draft damper 16 further is arranged 10 to be completely closed before the motor begins to operate; as otherwise, the blower would force the gases of combustion through the open check into the boiler room. The check draft damper 16 illustrated is preferably of the gravity closing type 15 and mechanisms for opening and closing it in the manner hereinbefore set forth will be described hereinafter.

The various instruments for controlling the operation of the boiler 10 through control of the 20 motor 14 and blower 12 and the check draft damper 16 are preferably located adjacent the boiler on a control board panel 20.

In order to operate the motor 14, it is connected 25 to a suitable available source of current supply.

Lines 22 from a suitable electric power supply source may be brought to a conventional splice box 24 mounted on the control panel 20. From the splice box 24, the main power supply is connected to the customary main line fused safety 30 switch 26 of the double pole, manually operated type. In turn, one lead from the main switch may be connected in series with one side 28 of a cutout switch (thermal overload) 30 through the splice box 24 to one terminal 32 of the motor 14. 35 The other lead from the main switch 26 is connected in series with a manually operable variable rheostat 34, a tiltably-operated mercoid switch 36 and the other side 38 of the cutout switch 28 through the splice box 24 to the second 40 terminal 40 of motor 14. It will be seen that, when the main line switch 26, the cutout switch 30 and the mercoid switch 36 are all closed, current will be supplied to drive the motor 14, the 45 amount of current supplied being controlled by varying the rheostat 34. The speed of the motor 14 is varied by the rheostat, thereby controlling, as desired, the quantity and pressure of the air supplied to the ashpit.

Under ordinary operating conditions, the main line fused switch 26 is kept closed and is only opened when repairs are to be made or the fuses in such switch are to be changed. The fuses in this switch serve their normal function of preventing injury to the apparatus due to excess current or injury to the main line due to a short circuit in the apparatus. The construction of the main line switch 26 is well known and, therefore, need not be described. The function of the 60 cutout switch 30 is to protect the forced draft blower motor 14 from current overload. It may be of any suitable construction, the one herein described being thermally operated so that when more than the fixed amount of current passes 65 through said switch, the excess heat produced will cause such switch to open. The cutout switch 30 is also ordinarily closed. Since the construction of such switches is well known, the details thereof need not be described.

The blower motor circuit is provided with a switch 36, preferably of the conventional mercury tube type, a well known example of which is the "Mercoid" switch. The operation of this switch is controlled, as will hereinafter be described, by 75

5 a pressurestat or aquastat to thereby suitably operate the blower motor. The construction and operation of such mercury tube switches being well known, it is not necessary to describe its specific structure.

10 Such switch is adapted to be opened or closed by being tilted and depends for its operation on a drop of mercury being moved, by tilting, in position to touch the two poles or contacts of said switch. The operation of this switch 36, which will be more fully described, is dependent upon the steam pressure or water temperature created by combustion in the boiler, being arranged to automatically close when the pressure or temperature in the boiler falls below a selected magnitude and open when it is raised to said selected magnitude.

15 After a boiler has been stoked and the temperature of the coal in the boiler is initially raised, a large quantity of combustible gases are given off by the coal. For reasons of safety, it is necessary, therefore, that these gases be completely burned before operation of the blower is stopped.

20 It will be apparent, should the blower operation cease under automatic control before such combustible gases are consumed, they will form a layer at the top of the coal bed. This comparatively large amount of unconsumed gas, when operation of the blower is again commenced, may become ignited by the resulting hot gases of combustion or by coming in contact with live coals in the fire bed, possibly resulting in an explosion.

25 For this reason, regardless of the pressure in the boiler, it is necessary to maintain the blowers in operation for a fixed period after any stoking to consume these gases. This period is usually from fifteen to thirty minutes.

30 To maintain the blowers in operation for this fixed period, I prefer to provide a time ignition switch 42. The time ignition switch 42 is connected in parallel with the mercoid switch 36. The time ignition switch 42 is manually closed after stoking and automatically will stay closed for a fixed period at the end of which period it will automatically open. It will be seen that when the time ignition switch 42 is closed current will be supplied to the motor 14 and that the blower 12 will operate to consume whatever combustible gases remain in the combustion chamber or furnace of the boiler. The specific construction of such time ignition switch is well known and, therefore, need not be described.

35 It is, of course, to be understood that in place of the time ignition switch 42 a simple manually operated switch might be employed which would be closed by the stoker of the boiler and opened by him after a fixed period has passed. However, since the use of such manually operated switch would require the attention of the stoker and would result in a considerable waste of his time, as well as the danger of his forgetting to open the switch, it is preferred that the automatically opening time ignition switch 42 be employed.

40 It will be apparent that when the time ignition switch 42 is opened, the operative opening and closing of the blower motor circuit will be controlled by the mercury tube switch 36, which, in cooperation with the check draft damper 16, controls the pressure at which the boiler is operated. The means for controlling this check draft damper will be hereinafter described.

45 In the present system, it is intended to operate the boiler under two different automatic oper-

5 ating conditions, one required for daytime heating and the other required for nighttime heating. During the day, as heretofore stated, the boiler fuel combustion is controlled by a pressurestat, which maintains the desired boiler steam pressure. During the night, boiler fuel consumption is controlled, as hereinafter described, by an aquastat, to maintain the desired boiler water temperature.

10 To accomplish this, I provide two separate means for controlling both the mercury tube switch 36 and the check draft damper, one for daytime use and the other for nighttime use. While manual means might be employed to shift from the daytime control to the nighttime control, it is preferred that automatic means be utilized in order that no attention thereto will be required.

15 For this purpose, I first provide a conventional time switch which comprises a schedule clock 20 44, adapted to maintain the switch 48 closed for a selected period of time and then open it for another selected period before closing it again. Inasmuch as the construction of such time switch is well known, it will not be here described. In the 25 present embodiment of my invention, the schedule clock is arranged to close the switch 48 during the day and to open it at night. In the arrangement illustrated in Figure 2, I have shown the clock mechanism of the schedule clock 44 connected to the main power supply through a fuse block 46, which fuse block is intended to prevent injury to the windings of the schedule clock. The switch 48 of the schedule clock is arranged to open and close a circuit in a day-night change- 30 over relay 50.

20 The relay 50 has a solenoid 52 having one lead therefrom connected directly to one leg of the main line fused switch 26 and the other lead connected to the other leg of the main line fused switch through the schedule clock switch 48. When the schedule clock switch 48 is closed, current will flow through the solenoid 52. This will attract and further draw in a movable iron core 54 arranged partly within the solenoid. Two 45 movable contacts 56, insulated from each other, are arranged on, and adapted to move with, said movable iron core 54 and to make contact with two upper stationary poles 58. The upper stationary poles 58 are connected to the daytime 50 control for the mercury tube and check draft damper. It will be seen that, when the schedule clock switch 48 opens, current will no longer flow through the solenoid 52 and the iron core 54 and the two movable contacts 56 will descend, breaking their contact with the upper stationary poles 58 and making contact with the lower stationary poles 60. The lower stationary poles 60 are connected to the control for nighttime operation. 60 The movable contacts 56 are connected to the circuits which control the mercury tube switch and the check draft damper in a manner which will hereinafter be described, and it will be seen that by moving these contacts so that they touch 65 the stationary poles 58 or the stationary poles 60 either the daytime or the nighttime control instruments will govern the operation of the mercury tube switch and the check draft damper.

70 It is, of course, to be understood that in place of the schedule clock and the day-night change-over relay 50 manually-operated means, such as the usual double pole, double throw switch, might be employed. However, the automatic means above described are preferred.

However, whenever it may become desirable to operate the boiler under nighttime control conditions continuously at any time, for example in the early fall or late spring, when the heating load is extremely light, or in the summer time, when the heating boiler is used, with well known apparatus, such as submerged heaters, to operate a hot water boiler, I have provided a manual switch 62, the one illustrated being of the toggle variety in series with the schedule clock switch 48. This switch 62 may be manually opened to thereby open the schedule clock switch circuit, so that no current will pass through the solenoid and the movable contacts 56 will, therefore, be kept continually in contact with the stationary poles 60 to thereby maintain the nighttime controls in control of the operation of the boiler.

It will, of course, be understood that when it is desired to operate the boiler continuously under daytime conditions, the schedule clock may be arranged to continuously maintain closed the switch 48 for the desired period of operation.

Ordinarily, however, the switch 62 is kept closed and the schedule clock automatically changes from daytime to nighttime operating temperatures and pressures.

The remaining instruments to be described are control instruments and are adapted to be operated with a voltage lower than that supplied by the power supply line 22. In order to obtain this lower voltage, I provide a step-down transformer 64. The primary of the step-down transformer 64 is connected to the main line fused switch 26. The secondary is connected to the various control instruments in a manner that will be hereinafter described.

To provide for daytime control of the boiler, I prefer to arrange on the control board panel 20 a modulating steam pressure regulator (presurestat) 66, and to provide for nighttime control I arrange a modulating vapor pressure regulator (aquastat) 68 on the same panel. The steam pressure regulator 66 is connected by a pipe 71 of comparatively small diameter to the steam header 70 of the boiler. This pipe enters a sensitive bellows 72 arranged in the steam pressure regulator. The bellows 72 are adapted to be extended when the pressure in the main header 70 rises and to contract when the pressure in the main header 70 falls. To the end of the bellows 72, I connect the movable arm 74 of a potentiometer 76. It will be apparent that this arm 74 will move across the potentiometer in relation to the rising or falling of pressure in the steam header 70. The ends of the resistance 78 of the potentiometer 76 are connected to the upper stationary poles 58 of the change-over relay 50, and, when the movable contacts 56 of the relay are in their upper position, the resistance 78 is connected to the rest of the control circuit.

While I have illustrated my invention as applied to a single boiler, it will be understood that it may be applied to a battery of two or more boilers, each of which is connected to one or more blowers. In such case, the pipe 71 is connected to the common steam header.

The modulating water or vapor temperature regulator 68, which is a conventional aquastat, is intended for nighttime control and is arranged, therefore, to be operated by the boiler water temperature or by boiler vapor temperature. I prefer, therefore, to connect this aquastat by means of a pipe of comparatively small diameter to a bulb 69 arranged in the boiler just below or just above the hot water line. This pipe is connected

in the modulating vapor temperature regulator 68 to a sensitive bellows 80. Any suitable gas is sealed in the bulb 69, the bellows 80 and the pipe connecting the change in the temperature of the water or the vapor just above the water line will effect corresponding movement of the bellows 80, thereby providing a relatively sensitive instrument for nighttime control. Where two or more boilers are to be used, the bulb is arranged in such place where it will be controlled by the temperature common to all. The movable arm 82 of a potentiometer 84 is arranged on the moving end of the bellows 80 and, therefore, will move in accordance with the temperature of the water in the water coils in the boiler. The two ends of the resistance 86 of the potentiometer 84 are connected to the lower stationary poles 60 of the change-over relay 50 and the resistance 86 is adapted to be arranged into the control circuit when the moving contacts 56 are in touch with the lower stationary poles 60.

It will, therefore, be apparent that the change-over relay 50, which is controlled by the schedule clock 44, will bring either the modulating steam pressure regulator 66 or the modulating vapor temperature regulator 68 into the control circuit to control the operation of the boiler during the day or during the night.

I have already described how the movement of the potentiometer arm 74 and the movement of 30 the potentiometer arm 82 are controlled respectively by the steam pressure or vapor or water temperature in the boiler. I will now describe how these movements in turn affect the closing of the mercury tube blower switch and the opening of the check damper 16.

For the purpose of simplifying the following explanation, I assume that the apparatus is set for daytime operation as illustrated in Fig. 2 and that the resistance 78 has both ends thereof connected to the upper stationary poles 58 and that the change-over relay 50 has its movable contacts 56 arranged in contact with the upper stationary poles 58.

It will be seen that one end 88 of resistance 78 45 of the potentiometer 76 is connected through the change-over relay 50 and through a coil 100 to one end 98 of a resistance 94, both of the latter forming part of a modulating electric compensator 97. The resistance 94 is part of a potentiometer 96. The other end 92 of the resistance 94 is in turn connected back through the coil 90 and the change-over relay 50 to the other end 102 of the resistance 78. It will be seen, therefore, that resistance 78, coil 90, resistance 94 55 and coil 100 are all arranged in series in a closed circuit which comes back to resistance 78.

Arm 74 of potentiometer 76 may be then connected to one end of the secondary of the step-down transformer 64 and the other end of the 60 secondary of the step-down transformer 64 is connected to the arm 104 of the potentiometer 96. It will be seen that the current will flow between the two arms through the resistances and will be divided through the coils 90 and 100. It 65 will furthermore be apparent that by adjusting the potentiometer arms the current flowing in coils 90 and 100 may be made equal. After the currents in coils 90 and 100 are equal, if the arm 74 is moved, due to the movement of the bellows 72 caused by a change in the pressure in the steam line, the amount of current flowing through coils 90 and 100 will be changed and more current will flow through one coil than the other.

The coils 90 and 100 form part of a pendulum type of switch 106. The switch 106 consists of an inverted U-shaped soft iron core 108 having its two legs partially arranged within coils 90 and 100, respectively, said core 108 being pivoted at the center thereof. A contact arm 110 is arranged on the soft iron core 108 and is adapted to swing with said core and be tilted to make contact with either of two fixed poles 112 and 113.

It will be seen that when the amount of current in coil 90 is greater than that in coil 100, greater force will be exerted on the leg of the soft iron core arranged therein than is exerted on the leg arranged within the coil 100 and thus the soft iron core will tilt, thereby tilting the contact arm 110 and cause it to make contact with the fixed pole 112. Conversely, when there is greater current passing through coil 100 the tiltable contact arm will tilt to the right and make contact with the fixed pole 113.

The tiltable contact arm 110 is connected to one end 111 of the secondary step-down transformer 64, the other end 115 of the step-down transformer 64 being connected to the common terminal of a conventional reversible motor 114. The construction of such motors being well known, motor 114 will not be here described. The two poles 112 and 113 of the pendulum type switch 106 are connected to the reversible motor 114. These poles are so connected with the motor coils of motor 114 that when the tiltable arm 110 touches the fixed pole 112 it drives the motor in one direction, and when it touches the fixed pole 113 it drives the motor in the opposite direction. In the embodiment illustrated, I prefer to arrange the motor 114 so that when the tiltable contact arm 110 touches the fixed pole 113 the shaft 116 of the reversible motor 114 will turn in a counterclockwise direction, as shown in the drawings, and when the tiltable contact arm touches the fixed pole 112 the shaft will turn in a clockwise direction.

The shaft 116 of the reversible motor 114 is connected to the movable arm 104 of potentiometer 96 by any suitable arrangement such as the crank and link 118. Thus, when the motor moves, the potentiometer arm will move over the resistance 94. On the same shaft 116, I arrange a long arm 120, on one end of which I arrange the mercury tube switch 36. The other end of said arm 120 is connected by any suitable means such as a cable, chain, or rope 122 over pulleys 124 and 126 to the check draft damper 16.

The operation of the control device will now be described.

Let us assume that the motor 14 is operating the blower 12 and thereby raising the pressure within the boiler. That is the condition illustrated in Fig. 2 where the globule of mercury in the mercury tube 36 is shown connecting the two contact points in such switch thereby closing the motor circuit. As the pressure in the steam header 70 begins to rise, the bellows 72 in the modulating steam pressure regulator 66 begin to expand, moving the potentiometer arm 74 to the right. As a result, the current in the potentiometer circuit is unbalanced and greater current flows through coil 90 than flows through coil 100. The tiltable contact arm 110 tilts and touches the fixed pole 112 thereby causing the shaft 116 of the motor 114 to move in a counterclockwise direction. When the motor moves in a counterclockwise direction, it rotates the long arm 120 in a counterclockwise direction.

It also moves the potentiometer arm 104 toward the left. The movement of the potentiometer arm toward the left will increase the amount of current flowing through coil 100 and when the amount of current in coil 100 is equal to the amount of current in coil 90 the tiltable contact arm 110 will be moved away from the fixed poles 113 and will remain between the fixed poles. As soon as the tiltable arm moves away from the fixed pole 113, the motor will cease to operate and the shaft 116 will stop turning. Since the currents in 90 and 100 are then equal, the potentiometer arms will stay fixed until further movement of the bellows 72, to again unbalance the amount of current passing through coils 90 and 100.

It will be observed that when the shaft 116 moves in a counterclockwise direction to thereby balance the current flowing through coils 90 and 100, the long arm 120 also moves counterclockwise. The mercury in the mercury tube switch moves away from the two contacts to thereby open the mercury tube switch upon the initial counterclockwise movement of the long arm 120. The further counterclockwise movement of the long arm 120 pulls the chain 122 which is connected with one end of the long arm 120 and opens the check damper 16.

To summarize this operation, it will be seen that when the pressure in the boiler increased, the control apparatus caused the mercury tube switch first to be opened and further increase of pressure in the boiler and, therefore, in the bellows 72 caused the check damper to open. It is most important to note that the opening of the damper is not abrupt, but that the damper opens more and more as the pressure rises.

After the motor has been shut off and the check draft damper opened a certain distance, the pressure in the boiler may start to fall. When the pressure in the boiler starts to fall, the bellows 72 will contract, moving the potentiometer arm 74 toward the end 88 of the resistance 78. This will in turn cause greater current to flow through coil 90, to thereby tilt the tiltable contact arm 110 to make contact with the fixed pole 113 and thereby cause the reversible motor 114 to be rotated in a clockwise direction. Again, the potentiometer arm 104 will be moved in a direction to increase the current in coil 90 until the current in the coils 90 and 100 are balanced. At the same time, the arm 120 will be rotated clockwise, thereby releasing tension on the chain 122 connecting it to the check damper and allowing the check damper to close, and then, only after the check damper has been completely closed, will the globule of mercury in the mercury tube switch 36 close the contact therein.

From the foregoing description, the operation of the modulating vapor temperature regulator will readily be understood when it is shifted into place of the modulating steam pressure regulator by the action of the schedule clock 44. The potentiometer arm 82 of the modulating vapor temperature regulator 68 is electrically connected to the potentiometer 74 of the modulating steam pressure regulator 66. The potentiometer resistance 86 of the modulating vapor pressure regulator 68 is connected to the contact 60 and when the relay is in nighttime operating position it is connected to the movable contacts 56 instead of the resistance 78 of the modulating steam pressure regulator 66. Thus, it is apparent that the modulating steam pressure regulator or the modulating vapor or water temperature regu-

lator by the mere operation of the daytime-nighttime change-over relay 50 are substituted in the control circuits in place of each other and operate similarly except that they operate at 5 different temperatures and pressures.

It is to be understood that the predetermined pressure or temperature at which the boiler operates may be changed by adjusting either of the bellows or the positions of the potentiometer 10 arms with respect to their bellows. Other means of adjusting this predetermined pressure or temperature will readily occur to one versed in the art and will, therefore, not be described.

To recapitulate, it will be apparent that by 15 the arrangement of the automatic controls illustrated, I have eliminated the necessity of periodic high rates of fuel combustion per unit of boiler grate surface heretofore required with other systems and methods of control. With the system 20 described, the combustion of fuel is enabled to take place in the fuel bed and the relatively ample space above the fire zone, provided in all conventional boilers, may, therefore, be used for the storage of fresh fuel not possible with conventional systems and methods of control here- 25 tofore used with the cheaper and smaller grades of coal such as anthracite, buckwheat, rice, barley, bituminous slack, waste fuels and the like.

These results are in short accomplished by 30 utilizing, under the proper control described, in combination forced draft and natural chimney draft, there being no control of the latter except the automatic check draft described. Such controls are the pressurestat and aquastat for automatically and continuously maintaining the 35 boiler at the selected operating conditions, the time clock switch for automatically changing from daytime to nighttime operating conditions and back again and the time switch to eliminate 40 the possibility of explosion of unburned gases after stoking.

While I have described the construction and operation of the present system and its apparatus in particular detail, I do not wish to be 45 limited to the specific details herein set forth, but intend to claim the invention as broadly as the state of the prior art and the scope of the appended claims permit. Accordingly, while I have described the apparatus as adapted to operate 50 only a single forced draft blower and a single check draft damper, the system and apparatus herein described can be readily adapted to operate several blowers, several dampers and, therefore, several different boiler units.

55 I claim:

1. A combustion control system for a boiler having a breeching and burning solid fuel comprising, in combination, a motor driven blower operatively connected to said boiler, a check 60 draft damper arranged in the breeching, an electric circuit for said blower motor, a switch arranged in said blower circuit and adapted to open and close said blower circuit, electromagnetic means operatively connected to both the damper 65 and the switch for opening and closing said switch and said damper, pressure controlled means responsive to the steam pressure in said boiler for operating the electromagnetic means, temperature controlled means responsive to the 70 temperature of the boiler water or boiler vapor for operating the electromagnetic means, a relay connected to the pressure controlled means, temperature controlled means and the electromagnetic means, said relay being adapted to operate- 75 tively connect either the pressure controlled

means or the temperature controlled means to the electromagnetic means, a circuit for operating said change-over relay, a time schedule switch arranged in the relay circuit and adapted to control said relay. 5

2. A combustion control system for a boiler having a breeching and burning solid fuel comprising, in combination, a motor driven blower operatively connected to said boiler, a check 10 draft damper arranged in the breeching, an electric circuit for said blower motor, a switch arranged in said blower circuit and adapted to open and close said blower circuit, electromagnetic means operatively connected to both the 15 damper and the switch for opening and closing said switch and said damper, pressure controlled means responsive to the steam pressure in said boiler for operating the electromagnetic means, temperature controlled means responsive to the temperature of the boiler water or boiler vapor 20 for operating the electromagnetic means, a relay connected to the pressure controlled means, temperature controlled means and the electromagnetic means, said relay being adapted to operatively connect either the pressure controlled 25 means or the temperature controlled means to the electromagnetic means, a circuit for operating said change-over relay, a switch arranged in the relay circuit and adapted to control said relay. 25

3. In a combustion control system for a boiler 30 having a breeching and burning solid fuel, in combination, a check draft damper arranged in the breeching, electromagnetic means operatively connected to the damper for opening and closing said damper, pressure controlled means responsive to the steam pressure in said boiler for operating the electromagnetic means, temperature controlled means responsive to the temperature of the boiler water or boiler vapor for operating the electromagnetic means, a relay connected to the pressure controlled means, temperature controlled means and the electromagnetic means, said relay being adapted to operatively connect either the pressure controlled 35 means or the temperature controlled means to the electromagnetic means, a circuit for operating said relay, a time schedule switch arranged in the relay circuit and adapted to control said relay. 40

4. In a combustion control system for a boiler 45 having a breeching and burning solid fuel, in combination, a check draft damper arranged in the breeching, electromagnetic means operatively connected to the damper for opening and closing said damper, pressure controlled means responsive to the steam pressure in said boiler for operating the electromagnetic means, temperature controlled means responsive to the temperature of the boiler water or boiler vapor for operating the electromagnetic means, a relay connected to the pressure controlled means, temperature controlled means and the electromagnetic means, said relay being adapted to operatively connect either the pressure controlled means or the temperature controlled means to the electromagnetic 55 means, a circuit for operating said relay, a switch arranged in the relay circuit and adapted to control said relay. 60

5. A combustion control system for a boiler 65 having a breeching and burning solid fuel comprising in combination a motor driven blower operatively connected to said boiler, a check draft damper arranged in the breeching, an electric circuit for said blower motor, a switch arranged in said circuit and adapted to open and close said 70

circuit, a reversible electrical motor having a rotatable shaft, an arm arranged on said reversible motor shaft operatively connected to the switch in the blower motor circuit and to the check draft damper, means controlled by the pressure in the boiler for operating the reversible motor, said means being adapted to turn the reversible motor shaft in one direction when the pressure in the boiler increases and in the opposite direction when the pressure decreases.

6. A combustion control system for a boiler having a breeching and burning solid fuel comprising, in combination, a motor driven blower operatively connected to said boiler, a check draft damper arranged in the breeching, an electric circuit for said blower motor, a tiltably operated mercury tube switch arranged in said circuit and adapted to open and close the circuit, a control device for said mercury tube switch and said check draft damper comprising a reversible motor having a shaft, an arm arranged intermediate its ends on said shaft and having one end thereof operatively connected to the check draft damper, the other end thereof having the mercury tube switch arranged thereon, an electric circuit for said reversible motor, a movable switch for controlling the direction of rotation of the motor, means for controlling movement of said switch, a pair of potentiometers having their resistances connected in parallel, the switch movement controlling means being operatively connected to said resistances, the arms of the potentiometers being connected to a source of current, the arm of one of said potentiometers being movably connected to the motor shaft, means responsive to the steam pressure or water or vapor temperature in the boiler for moving the arm of the other of the potentiometers.

7. A combustion control system for a boiler having a breeching and burning solid fuel comprising, in combination, a motor driven blower operatively connected to said boiler, a check draft damper arranged in the breeching, an electric circuit for said blower motor, a tiltably operated mercury tube switch arranged in said motor circuit and adapted to open and close said circuit, a pivoted arm having one end thereof connected to the check draft damper and having the mercury tube arranged on the other end thereof, means controlled by the pressure in said boiler for tilting said arm, said pivoted arm, check draft damper and mercury tube being arranged relatively to each other so that upon tilting of the arm in a direction to open said check draft damper, the mercury tube switch is first opened before the initial opening movement of the check draft damper.

8. A combustion control system for a boiler having a breeching and burning solid fuel comprising, in combination, a motor driven blower operatively connected to said boiler, a check draft damper arranged in the breeching, an electric circuit for said blower motor, a tiltably operated mercury tube switch arranged in said circuit and adapted to open and close the circuit, a control device for said mercury tube switch and said check draft damper comprising a reversible motor having a shaft operatively connected to the check draft damper and the blower motor switch, an electric circuit for said reversible motor, a movable switch for controlling the direction of rotation of the motor, means for controlling movement of said switch, a pair of potentiometers having their resistances connected in parallel, the

switch movement controlling means being operatively connected to said resistances, the arms of the potentiometers being connected to a source of current, the arm of one of said potentiometers being movably connected with the motor shaft, means responsive to boiler conditions for moving the arm of the other potentiometer.

9. A combustion control system for a boiler having a breeching and burning solid fuel comprising, in combination, a motor driven blower operatively connected to said boiler, a check draft damper arranged in the breeching, an electric circuit for said blower motor, a blower motor switch arranged in said circuit and adapted to open and close the circuit, a control device for said blower motor switch and said check draft damper comprising a reversible motor having a shaft, an arm arranged intermediate its ends of said shaft and having one end thereof operatively connected to the check draft damper, the other end thereof being operatively connected to the blower motor switch, an electric circuit for said reversible motor, a movable switch for controlling the direction of rotation of the motor, means for controlling movement of said switch, a pair of potentiometers having their resistances connected in parallel, the switch movement controlling means being operatively connected to said resistances, the arms of the potentiometers being connected to a source of current, the arm of one of said potentiometers being movably connected with the motor shaft, means responsive to boiler conditions for moving the arm of the other potentiometer.

10. A combustion control system for a boiler having a breeching and burning solid fuel comprising, in combination, a motor driven blower operatively connected to said boiler, a check draft damper arranged in the breeching, an electric circuit for said blower motor, a blower motor circuit switch adapted to open and close said circuit, a control device for the motor circuit switch and the check draft damper comprising a reversible motor having a shaft, said shaft being operatively connected to the check draft damper and the motor circuit switch, an electric circuit for the reversible motor, a movable switch arranged in the reversible motor circuit for controlling the direction of rotation of the reversible motor, a pair of coils for controlling the movement of the movable switch, a pair of potentiometers having their resistances connected in parallel by the coils, the arms of one of said potentiometers being movably connected with the reversible motor shaft, means responsive to boiler conditions for moving the arm of the other potentiometer.

11. A combustion control system for a boiler having a breeching and burning solid fuel comprising, in combination, a motor driven blower operatively connected to said boiler, a check draft damper arranged in the breeching, an electric circuit for said blower motor, a tiltably operated mercury tube switch arranged in said motor circuit and adapted to open and close said circuit, a pivoted arm, means controlled by the pressure in said boiler for tilting said arm about its pivot, means connecting one end of the pivoted arm to the check draft damper and adapted to open said check draft damper upon tilting movement of said pivoted arm in one direction and adapted to close said check draft damper upon tilting movement in the opposite direction, said pivoted arm having the mercury tube switch arranged on the other end thereof to open and close the said

switch upon corresponding tilting of the said pivoted arm, said pivoted arm, check draft damper, mercury tube, and damper opening and closing means being arranged relatively to each other so that upon the pivoted arm being tilted in one direction about its pivot, the check draft damper

is closed before the mercury tube switch is closed and upon the pivoted arm being tilted in the other direction about its pivot, the switch is opened before the check draft damper is opened.

CHARLES H. SMITH.
